UNITED STATES PATENT OFFICE.

WILLARD H. KEMPTON, OF WILKINSBURG, PENNSYLVANIA, ASSIGNOR TO WESTINGHOUSE ELECTRIC & MANUFACTURING COMPANY, A CORPORATION OF PENNSYLVANIA.

STRAIN INSULATOR.

Application filed October 17, 1918. Serial No. 253,624.

To all whom it may concern:

Be it known that I, WILLARD H. KEMPTON, a citizen of the United States, and a resident of Wilkinsburg, in the county of Allegheny and State of Pennsylvania, have invented a new and useful Improvement in Strain Insulators, of which the following is a specification.

My invention relates to strain insulators, and it has for its primary object the construction of such insulators by employing suitable connector elements held in spaced relation with respect to each other by layers of sheet material impregnated with a hardened binder.

One object of my invention is the provision of strain insulators of such construction that they shall be highly resistant to strains applied in any direction.

Another object of my invention is the construction of strain insulators which, being unaffected by wide temperature changes, moisture, oils, weak acids and alkalis, may be employed under adverse atmospheric conditions.

A still further object of my invention is the provision of easily constructed, compact strain insulators possessing high insulating qualities and great mechanical strength.

With these and other objects in view, my invention will be more fully described, illustrated in the drawing, in which like numerals indicate like parts, and then particularly pointed out in the appended claims.

In the drawings, Fig. 1 is an end view, partly in section and partly in elevation, of a strain insulator embodying my invention; and Fig. 2 is a plan view, partly in elevation and partly in section, of the strain insulator shown in Fig. 1.

In practicing my invention, I may construct a strain insulator by first preforming a plate or spacer member by stacking sheets of suitable size and material, impregnated with a binder, the sheets being stacked until a proper thickness has been reached, after which they may be subjected to heat and pressure to compact the material and harden the binder.

Connector elements may be formed of wires or other suitable material by bending each wire so that a loop, having extending ends substantially parallel to each other, is formed and the extending parallel ends may

be roughened in any suitable manner. A 55 loop thus formed may be placed at each end of the spacer member or plate in such manner that the extending parallel ends of the loop may engage the side edges of the spacer member and the loop may project 60 beyond it. A sheet material impregnated with a suitable binder may then be wound about the spacer member having the ends of the loop engaging it, and the body thus formed may be placed in a mold and subjected to heat and pressure, thus compacting the windings of sheet material about the spacer member and hardening the binder so that the connector elements are firmly secured in place and a hard unitary body results.

Referring to the drawings, a strain insulator 1 embodying my invention is shown which may be constructed by preforming a spacer member 2 of sheet material impregnated with a suitable binder such, for instance, as a phenolic condensation product. The sheet material impregnated with a binder may be stacked to a suitable thickness and subjected to heat and pressure to 80 compact it and harden the binder. The spacer member 2 is preferably constructed in this way but may consist of a plate of any suitable insulating material.

Connector elements 3 may be formed by 85 bending wires or other suitable elements so that loops, having extending ends 4, substantially parallel to each other, may be provided. The ends 4 may be roughened by twisting or bending them or they may be 90 roughened by grooving their surfaces, and a connector element thus formed may be placed at each end of the spacer member 2 so that the ends 4 may engage the side edges of the spacer member and the loops may 95 project beyond it.

A sheet material 5, which may be paper, duck, cotton batting or any other fibrous material may be impregnated with a suitable binder, such as a phenolic condensation 100 product, and then dried to facilitate its handling. The sheet material thus treated may be wound about the spacer member 2 and the ends 4 of the connector elements 3 until a desirable thickness has been reached, 105 after which the body may be placed in a mold and subjected to heat and pressure to compact the material 5 and to harden

the binder with which it is impregnated. The intermediate portion 6 between the ends 4 of the respective connector elements 3 may be filled in with the material 5 of less 5 width so that, when the body is completed, an even surface will be provided.

The spacer member and the outer windings of the material may be formed by employing the same material, or the spacer 10 member and the material enclosing it may differ, if desired. The binder employed is preferably a phenolic condensation product, as it possesses high insulating qualities, as 15 well as great mechanical strength, when employed as a binder for fibrous material. A strain insulator formed as herein disclosed, after being subjected to heat and pressure, possesses great mechanical strength and is 20 very compact, as well as possessing high insulating qualities.

Although I have described specifically a strain insulator embodying my invention, it is obvious that minor changes may be made 25 in the construction thereof without departing from the spirit of my invention and I desire, therefore, that only such limitations shall be imposed as are indicated in the appended claims.

I claim as my invention:

- 30 1. A method of constructing strain insulators that comprises preforming an insulating spacer member, disposing loop connector elements at the ends thereof, the ends of said elements being on opposite sides of said member and securing the connector elements in place by winding layers of impregnated sheet material about the ends of the connector elements and the spacer member.
- 35 2. A method of constructing strain insulators that comprises stacking sheets of material impregnated with a phenolic condensation product, subjecting the stacked sheets to heat and pressure, bending wires to form loops each of which has projecting substantially parallel ends, disposing a loop at each end of the spacer member in such manner that the parallel ends engage the sides of the spacer member and the loops extend beyond it, winding sheet material impregnated 40 with a phenolic condensation product about the ends of the wires and the spacer member and subjecting the body thus formed to heat and pressure.

3. A method of constructing strain insulators that comprises preforming an insulating spacing member, disposing loop connector elements at the ends thereof, the ends of said elements being on opposite sides of said member, securing the connector elements in place by winding impregnated sheet material about the ends of the connector elements and the spacer member and applying heat and pressure to the body thus assembled to compact the material and to harden the binder.

4. A method of constructing strain insulators that comprises impregnating a plurality of sheets of fibrous material, stacking the sheets to provide a composite plate, applying heat and pressure thereto to compact the material and to harden the binder, disposing connector elements at the ends thereof and securing the connector elements in place by winding impregnated sheet material about the ends of the connector elements and the spacer member.

5. A method of constructing strain insulators that comprises impregnating a plurality of sheets of fibrous material, stacking the sheets to form a composite plate of desirable thickness, applying heat and pressure thereto to compact the material and to harden the binder, disposing connector elements at the ends thereof, impregnating a sheet of fibrous material with a binder and winding the impregnated sheet material about the ends of the connector elements and the spacer member and applying heat and pressure to the body thus assembled to compact the last mentioned fibrous material and to harden the binder contained therein.

6. A method of forming a strain insulator that comprises impregnating a sheet of fibrous material with a binder, positioning a pair of connector elements at opposite ends of an insulating spacer element, winding the treated sheet about the spacer element and adjacent ends of the conductor elements to form a sleeve containing a plurality of convolutions of the sheet material and subjecting the article thus assembled to heat and pressure.

In testimony whereof, I have hereunto subscribed my name this 25th day of September, 1918.

WILLARD H. KEMPTON.
